ARCHIE OAKES, OF DETROIT, MICHIGAN, ASSIGNOR TO SQUARE D. COMPANY, OF DETROIT, MICHIGAN, A CORPORATION OF MICHIGAN.

QUICK-BREAK DOUBLE-THROW SWITCH.

1,359,732.

Specification of Letters Patent. Patented Nov. 23, 1920.

Application filed June 10, 1918. Serial No. 239,119.

To all whom it may concern:

Be it known that I, ARCHIE OAKES, a citizen of the United States, residing at Detroit, in the county of Wayne and State of Michigan, have invented certain new and useful Improvements in Quick-Break Double-Throw Switches, of which the following, taken in connection with the accompanying drawings, form a complete and exact description thereof.

My invention relates to quick break double throw switches generally. These switches may be of the inclosed type and one of the objects of my invention is to provide for the external operation of said double throw quick break switch.

A further object of my invention is to provide for a quick break at either limit of the stroke.

20 A further object of this invention is to generally simplify a construction of quick break switches, whereby a very rugged structure results.

25 A further object of this invention is to provide means, whereby an intermediate or neutral position may be assumed by the switch mechanism.

30 Other objects of this invention will in part be apparent and in part be further described in the detailed description following;

35 One of the many possible forms this invention may take is shown in the accompanying drawings, in which Figure 1 is a perspective view of the inclosed quick break double throw switch, with the cover shown in open position, the cover and casing being shown in dotted lines. Fig. 2 is a partial, longitudinal, medial sectional view of 40 the switch mechanism, with the casing and cover removed.

45 Referring now in detail to the drawings, it will be seen from Fig. 1 that the switch is inclosed in a casing, 1, provided with a cover 2, which may be locked in closed position through the medium of a hasp 3 and co-operating slot (not shown) in the cover and a padlock (also not shown). This cover is provided with a recessed portion 4 to accommodate the switch mechanism, whereby it is possible to operate the switch when the cover is closed.

50 The switch mechanism is operated by means of an external handle 5, rigidly joined, and in the example shown, integrally

with internal operating member 6. Said operating member 6, as will be seen from reference to Fig. 1 consists of a horizontal crank portion of a rod, which is pivotally mounted, substantially, centrally on either 60 side of the body portion, of the casing 1. This crank is adapted to swing from one extreme limit to the other, through the operation of the external handle 5.

The operating member 6 is journaled in 65 the horizontal link 7, which upon reference to Fig. 1 will be seen to consist of two members joined by means of suitable rivets, bolts or connecting members 8, intermediate the ends and also joined with suitable bearing 70 members 9. These bearing members 9 consist of rivets or bolts and suitable spacing tubes or casings 10, which are clearly shown in Fig. 2.

The link 7 is compelled to travel in such 75 a manner that it, at all times, occupies positions parallel to its initial position by means of end links 11, which are connected to the horizontal link 7 through the medium of the bearing members 9. The lower ends of 80 these links 11 are pivotally connected at 12 to supporting members 13, rigidly mounted upon the insulating base 14.

It will be seen from the above description that upon operation of crank 5, the link 7 85 may be caused to travel to the extreme limit of its stroke.

The switch blades 15, which are adapted to be thrown to either extreme position and engage the contacts 16 are pivoted at 17 90 to central contact members 18. The switch blades 15 are given their motion from the link member 7 by means of slotted links 19, which are mounted upon the intermediate connecting members 8 and are spaced by 95 means of suitable tubular members 20^a and washers 21. The slots of these links 19 are shown at 20 at their upper ends, and such links are adapted to slide upon the connecting members 8 and contact with said connecting members at either extreme end of the slot. The lower ends of these links are journaled upon the cross head 22 and said cross head is connected to the pivotal knife blades 15 by means of insulating bushings 100 23 and clamping members at 24. These bushings also form spacing members to properly position the lower ends of the links upon the cross head 22. The connecting members 8 are also connected to the cross 105 110

head 22 by means of springs 25, which tend to cause the connecting members 8 to contact with the lower portion of the slots 20, as shown for instance in Fig. 2.

5 The operation of the structure described above is as follows:

Upon the operating crank or handle 5 being moved to one extreme limit of motion, the link 7 is carried by the crank 6 10 and through the medium of the links 19, carries the cross head 22 and with it the pivotal blades 15 until the pivotal blades 15 engage the spring contacts 16.

When it is desired to open this switch 15 through the medium of the operating crank 5, the parallel link 7 moves upwardly and stretches the springs 25 and thereby places tension upon the cross head 22, tending to withdraw the knife blades 15 from the contact member 16.

When the connecting members 8 contact with the upper portion of the slots 20 of the links 19, the pivotal knife blades 15 are positively withdrawn from engagement with 25 the contact members 16, and when the frictional engagement between said blades and contacts reaches a sufficiently low value, the springs 25 cause the blades 15 to be quickly withdrawn from the contact 16, causing a 30 very quick break in the electrical circuit.

It will be seen that the above operation is true for either extreme position of the knife blades 15 and from the above construction, it will be seen that the applicant has provided a very simple and efficient double 35 throw quick break switch.

In certain cases it may be desirable to provide external means for locking the switch in neutral or inoperative position and 40 such means are shown in Fig. 1 on the outside of the casing 1. This locking means consists of a plate 26 fastened to the casing through the medium of a flange 28 and provided at either end with slots 29, which are 45 formed substantially on the arc of the circle. On this plate member 26, there is mounted a spring pressed member 30, which is loosely held in engagement with plate 26 by means of headed pins or rivets 31, coöperating with 50 the slots 29; the spring for outwardly pressing this member 30 is shown at 32, and it will be noted that the pressure is applied substantially, centrally to this member 30. The central portion of the member 30 is provided 55 with a notch or cut out 33, adapted to engage the vertical portion 34 of the operating crank or member 5. This member 30 is provided with inclined edges 35, which are adapted to allow the vertical member 34 60 to depress this blade or latch member 30, as said portion 34 rides along the inclined edges 35 until said member 34 snaps into the notch 33.

A finger piece 36 is provided upon the 65 latch member 30, by means of which said

latch member may be disengaged from the member 34. Alining openings are provided in the latch member 30 and the plate 26, which are adapted to receive the bail portion of a padlock shown in dotted line and 70 indicated by the reference numeral 37. By means of this padlock, it is possible to lock the switch in "off" or neutral position.

This latch member 30 performs a further function when the padlock 37 is removed in that it allows the switch to be thrown from one extreme position to the other extreme position only by a very rapid motion to said switch by means of the crank 5. This is possible because of the fact 75 that when the member 34 is rapidly passed along the inclined edges 35, the latch member 30 is shot inwardly and the momentum thereof temporarily withdraws the notch 33, overcomes the action of the spring 32, and 80 allows the member 34 to pass by the notch 33.

It will be seen from the above description of this outside lock or latching mechanism that several very desirable functions are performed. For instance, it is possible to lock 90 the switch in neutral position. It is also possible to temporarily retain the switch in neutral position and readily unlatch said switch operating mechanism, whereby it may be moved from neutral position and further 95 that it necessitates a quick motion from one extreme position to the other extreme position, when it is desired to throw the switch completely over.

In certain types and electrical systems, this 100 rapid change from one set of connections to the other is very desirable and the mechanism above described prevents the inadvertent slow change of connections. It is possible, however, to make said change of 105 connections by moving the crank slowly to neutral position, then depressing the finger piece 36 and moving the switch on over to the other extreme position. This, however, 110 it will be seen requires the deliberate operation of the operator and cannot be done inadvertently.

It will be seen from the above description that a very practical rugged type of quick break double throw switch has been designed, 115 which is practically fool proof and is also possessed of a great many desirable functions, as have been in part outlined above.

The above detailed description and drawings are to be interpreted in an illustrated 120 sense only and not in a limited sense, as it is intended that the invention shall be limited only as defined by the following claims:—

1. A quick break, double throw switch 125 having stationary and coöperating movable contacts, an operating member, and interposed means between said operating member and movable contacts including parallel link mechanism and resilient means coöperating 130

with said link mechanism for securing a quick break.

2. A quick break, double throw switch having stationary and coöperating movable contacts, an operating member, and interposed means between said movable contacts and operating member including a plurality of slotted links each of which coöperates to control each movement of the movable contacts.

3. A quick break, double throw switch having stationary and coöperating movable contacts, an operating member and interposed means between said movable contacts and operating member including a plurality of slotted links and having resilient means for securing a quick break, the said resilient means all coöperating to obtain said quick break.

4. A quick break, double throw switch having stationary and coöperating movable contacts, an operating member and interposed means, between said movable contact and operating member including a plurality of angularly disposed slotted links, all of which coöperate with said movable contacts for each movement thereof.

5. A quick break, double throw switch having stationary and coöperating movable contacts, an operating member, a parallel link mechanism interposed between said operating member and movable contacts and slotted links interconnecting said movable contacts and operating member.

6. A quick break, double throw switch having stationary and coöperating movable contacts, an operating member, a parallel link mechanism, interposed between said operating member and movable contacts and connected to said movable contacts through the medium of a slotted link, having resilient means.

7. A quick break, double throw switch having stationary and coöperating movable contacts, an operating member, a parallel link mechanism interposed between said operating member and movable contacts, and a plurality of angularly disposed slotted links interconnecting said movable contacts and said operating member.

8. A quick break, double throw switch having stationary and coöperating movable contacts, an operating member, a parallel link mechanism interposed between said operating member and movable contacts and connected to said movable contacts through the medium of a plurality of angularly disposed slotted links, having resilient means.

9. A quick break, double throw switch having a plurality of stationary and movable contacts, a cross head connecting said movable contacts, an operating member, intermediate means connecting said operating member and cross head including two angularly disposed members both coöperating for

positively controlling each motion of the movable contacts throughout the major portion of their movement.

10. A quick break, double throw switch having a plurality of stationary and movable contacts, a cross head connecting said movable contacts, an operating member, intermediate means connecting said operating member and cross head including angularly arranged members, provided with resilient means all of which coöperate for positively controlling the motion of the movable contacts throughout the major portion of their movement and for securing a quick break.

11. A quick break, double throw switch having a plurality of stationary and movable contacts, a cross head connecting said movable contacts, an operating member, intermediate means connecting said operating member and cross head, including two angularly disposed slotted links for positively controlling each motion of the movable contacts throughout the major portion of their movement.

12. A quick break, double throw switch having a plurality of stationary and movable contacts, a cross head connecting said movable contacts, an operating member, intermediate means connecting said operating member and cross head including two angularly arranged slotted links, having resilient means for positively controlling each motion of the movable contacts, throughout the major portion of their motion and for securing a quick break.

13. A quick break, double throw switch having a plurality of stationary and movable contacts, a cross head connecting said movable contacts, an operating member, interposed means between said operating member and cross head including a parallel link mechanism and means comprising slotted links connecting said parallel link and cross head for positively controlling the motion of the movable contacts throughout the major portion of their movement.

14. A quick break, double throw switch having a plurality of stationary and coöperating movable contacts, a cross head connecting said movable contacts, an operating member, a parallel link mechanism connected to said operating member, a plurality of slotted links connecting said parallel link to said cross head for positively controlling the motion of the movable contacts throughout the major portion of their movement.

15. A quick break, double throw switch having a plurality of stationary and movable contacts, a cross head connecting said movable contacts, an operating member, a parallel link mechanism directly connected to said operating member, intermediate connections between said parallel link and said cross head, including resilient means where-

by said movable contacts are controlled by operation of the movable member and a quick break secured.

16. A quick break, double throw switch having a plurality of stationary and co-operating movable contacts, a cross head connecting said movable contacts, an operating member, a link directly connected to said operating member and constrained to occupy parallel positions, a plurality of angularly disposed slotted links and resilient means, co-operating with the first mentioned link and with the cross head, whereby the movable contacts are positively actuated throughout the major portion of their

movement and resiliently actuated during a portion of their breaking movement.

17. A quick break, double throw switch comprising a plurality of stationary and movable contacts, a cross head connecting 20 said movable contacts, an operating member, a link directly connecting to said operating member, auxiliary links connected to the end of the first mentioned link and slotted links connecting said cross head and said 25 first mentioned link, whereby the movable contacts may be operated by manipulation of said operating member.

ARCHIE OAKES.
